UNITED STATES PATENT OFFICE.

GEORGE F. ROTH, OF NEWPORT, KENTUCKY, ASSIGNOR OF ONE-HALF TO OSCAR KLAUSMEYER, OF CINCINNATI, OHIO.

DESIGN FOR AN AUTOMOBILE LAMP CASING.

Application filed May 2, 1925. Serial No. 13,306. Term of patent 14 years.

To all whom it may concern:

Be it known that I, GEORGE F. ROTH, a citizen of the United States, residing at 518 Maple Avenue, Newport, in the county of Campbell and State of Kentucky, have invented a new, original, and ornamental Design for an Automobile Lamp Casing, of which the following is a specification, reference being had to the accompanying drawing, forming part thereof.

In the drawing: Figure 1 is a perspective side view of the lamp body, and Figure 2 is a front view thereof.

I claim:

The ornamental design for an automobile lamp casing as shown.

GEORGE F. ROTH.
